UNITED STATES PATENT OFFICE.

JOHN B. ALLINGTON, OF ROCHESTER, NEW YORK.

GAS-HEATED FURNACE.

Application filed August 2, 1926, Serial No. 126,406. Renewed August 17, 1928.

The present invention relates to gas heated furnaces and an object of the invention is to provide a construction which may be made from a minimum amount of cast iron with 5 maximum radiating surface and will require little or no machining and is easy to assemble. A further object of the invention is to provide a novel construction which may be built up from units to produce a desired 10 amount of radiating surface.

To these and other ends, the invention consists of certain parts and combinations of parts, all of which will be hereinafter described: the novel features being pointed out 15 in the appended claims.

In the drawings:—

Fig. 1 is a view showing a portion of the shell of the furnace removed to expose the units, some of which are in vertical section; 20 Fig. 2 is a view of one of the units; Fig. 3 is a section on the line 3—3, Fig. 2; Fig. 4 shows a sectional view through the shell with the units in elevation, the burner being removed; 25 Fig. 5 is an enlarged section showing the manner of securing the legs or supports to the furnace.

Figs. 6 and 7 are respective top and side view of one of the supports; and 30 Fig. 8 is an enlarged view of one of the units.

Referring more particularly to the drawings, 1 indicates an outer sheet metal shell forming a heating chamber from which flues 35 2 lead to any suitable point. Within this shell is arranged an elongated combustion chamber *a*, and an elongated flue chamber *b* connected with the combustion chamber by a plurality of flues *c*. In this instance, the combustion 40 chamber is formed of a plurality of sections 3 each formed at opposite ends with internally projecting flanges 4 provided with bolt openings 5, the lower portion of the flanges being notched at 6 to provide a seat 45 for a gas burner 25^a. These sections are held together by bolts 7, a suitable packing if desired being interposed between the sections to form a tight joint between them. In addition to the sections outer sections 3^a may be 50 employed which are bolted to the outermost sections 3 and also about an opening 8 in the shell, outside plates 9 being bolted over these openings 8 and having preferably hinged doors 10 through which the interior of the combustion chamber may be reached, one of 55

the plates 9 having an opening 11 through which the burner may be projected.

Preferably from the top of each section of the combustion chamber a hollow radiating member 12 extends, said radiating member, in this instance, having fins or radiating projections 13 distributed over the surface thereof, the radiating member being of flat or elliptical cross section.

At its upper end the radiating member 60 connects with a section 14 of the flue chamber *b*, these sections 14 being preferably of substantially cylindrical form with internally projected annular flanges 15 at opposite ends thereof, said flanges being provided with bolt 65 openings 16 in order that these sections of the flue chamber may be connected in alignment by bolts 17, suitable packing rings if desired being interposed between the flanges to provide a tight joint between the sections. 70 The radiating member 12 connects with the section 14 at one side preferably above the bottom of the section. The form of the radiating member 12 is such that the center of the flue section 14 is directly above the center 75 of the combustion chamber section 3 and this radiating member lies in the plane of the combustion chamber section and the flue section, but is deflected to one side of the vertical 80 center line through the two sections. In this way it is possible to turn the radiating member 12 so that it projects or lies on either side of the center line, it being preferred to project one radiating member on one side of the center line and the next radiating member on 85 the opposite side of the center line so that sufficient air space is provided between the different radiator members as illustrated in Fig. 4 of the drawings. One of the end sections 14 of the flue may be closed by a plate 90 18 while the opposite end section may have a flue collar 19 bolted thereto to permit the flue 20^b to be connected to the flue chamber.

With the end in view of providing a uniform distribution of the heat throughout the 95 different units, so that any one unit will not conduct a greater supply of the gases than any one of the other units, an equalizing device is provided in the flue chamber. This equalizing device is in the form of a tube 25 extending through the flue chamber and tightly fitting the inner perimeters of the flanges 15. This tubular member is preferably closed 100 except by way of openings 26 in the bottom thereof, thus requiring the gases passing from 105

the radiating members to pass about the tube 25 before entering the tube. In this way each of the radiating members conducts substantially the same amount of heat from the combustion chamber. It will be seen also that the elongated flue chamber is through the flanges divided up into a number of separate compartments, each of which communicates through a restricted opening with the interior 10 of the tube at a point below the connection of a radiating member with a compartment. The tubular member acts as a retarding means for the products of combustion in the radiating members. It creates a pressure in 15 the radiating members so that the full effect of the products of combustion on the walls of the radiating members is obtained. This tubular member also acts to prevent the products of combustion from one radiating member passing downwardly through another radiating member.

It has been found that owing to the fact that the hollow radiating members 12 diverge or extend outwardly with reference to the 25 vertical plane of the burner chamber *a* the heat tends to flow close to the innermost wall of the chamber and in order to properly cause the disturbance of this flow of heat, baffles 27 are arranged in the hollow radial chambers 30 connecting two opposite side walls and spaced from the other two opposite side walls, being nearer to one of the latter side walls or the inner inclined walls than to the outer inclined walls, being nearer to the inner wall 35 than to the outer wall so that as the heat rises it heats these baffles and is deflected outwardly toward the outer side walls.

In order to support the combustion chamber, the flue chamber and the radiating members with the shell 1 of each combustion chamber section 3 may have on opposite sides vertical ribs 20 of dove tail cross section, for engagement by dove tail grooves 21 in upwardly projecting portions 22 on legs or supports 23, said legs or supports also having below said dove tailed groove 21 rests 24 for cooperating with the underside of a section of the combustion chamber. Any suitable number of these legs or supports 23 may be used to give the 40 desired support for the structure within the outer shell 1.

From the foregoing it will be seen that a gas burner disposed in the combustion chamber *a* will heat the latter and the products of combustion issuing therefrom will travel upwardly through the radiating members 12 through the flue chamber *b* and out through the outlet flue 20^a. The combustion chamber and the flue chamber are formed of sections, 50 one of the sections of each being connected to a section of the other through a radiating member forming with the two sections a unit. These units may be assembled together in any desired number to obtain a desired heating capacity, the units are reversible so as to pro-

ject on either side of a vertical line through the center of a combustion chamber section and the center of the flue chamber section. These units may be made of a single casting and do not require any considerable 70 amount of machine work thereon. They give maximum radiating surface for the amount of material contained therein. By having the radiating members connect with the flue chamber above the bottom of the latter, condensate will collect in the bottom of the flue chamber and will eventually be vaporized.

What I claim as my invention and desire to secure by Letters Patent is:

1. A gas furnace comprising a sectional 80 combustion chamber, a sectional flue chamber having its center vertically above the center of the combustion chamber, and radiating members each connecting a section of the combustion chamber with a section of the flue 85 chamber and being extended to one side of a center line through the centers of the two chambers.

2. A gas furnace comprising an elongated 90 combustion chamber, an elongated flue chamber, radiating members leading from the top of the combustion chamber and connecting with the side of a flue chamber above the bottom of the latter to provide a trap for condensate.

3. A gas furnace comprising an elongated 95 combustion chamber, an elongated flue chamber, a plurality of radiating members leading from the top of the combustion chamber, one behind the other and connecting with the flue chamber, proximate radiating members connecting with opposite sides of the flue chamber and being deflected in opposite directions laterally with reference to a center line through the flue chamber and the combustion 100 chamber.

4. A unit for gas heaters comprising a combustion chamber section, a flue chamber section having its center vertically above the combustion chamber section, and a radiating 105 member connecting the top of the combustion chamber section with the side of the flue chamber section.

5. A unit for gas heaters comprising a combustion chamber section, a flue chamber 110 section having its center vertically above the combustion chamber section, and a radiating member connecting the top of the combustion chamber section with the side of the flue chamber section above the bottom of the 115 latter.

6. A gas furnace comprising an elongated 120 combustion chamber, an elongated flue chamber, radiating members leading from the combustion chamber and connecting with the flue chamber above the bottom of the latter, partitions arranged in said elongated flue 125 chamber between the radiating members, hollow means associated with the partitions for providing compartments, said hollow means 130

being formed with openings below the connection of the radiating members with said flue chamber so that the gases from the radiating members pass around said hollow means before entering the latter through said openings.

7. A gas furnace comprising an elongated combustion chamber, an elongated flue chamber, partitions in said elongated flue chamber, a tube supported by said partitions within said elongated flue chamber, said tube having openings in its bottom, and radiating members connecting with the combustion chamber and with the flue chamber above the openings in said tube.

8. A gas furnace comprising an elongated combustion chamber, and an elongated flue chamber, arranged above the elongated combustion chamber, and radiating members extending upwardly and outwardly from the elongated combustion chamber and turned inwardly to connect with opposite sides of the elongated flue chamber, some of said radiating members projecting from one side of the plane of the elongated combustion chamber and the elongated flue chamber, and others of said radiating members projecting on the opposite side of said plane, being nearer to the innermost walls.

9. A gas furnace comprising an elongated combustion chamber, and an elongated flue chamber, arranged above the elongated combustion chamber, and radiating members extending upwardly and outwardly from the elongated combustion chamber and turned inwardly to connect with opposite sides of the elongated flue chamber, some of said radiating members projecting from one side of the plane of the elongated combustion chamber and the elongated flue chamber, and others of said radiating members projecting on the opposite side of said plane, and baffles arranged in said radiating members in spaced relation to the innermost and outermost walls of the latter, being nearer to the innermost walls.

10. A unit for gas furnaces embodying a combustion chamber section, a flue chamber section, a radiating member between them, a rib of dove-tail cross section on one side of the combustion chamber section, and a support having a groove receiving said rib and a rest below the groove for cooperating with the bottom of the combustion chamber section.

JOHN B. ALLINGTON.
